William A. Turner of Plymouth. North Carolina.

Letters Patent.

The whole referred to in these Letters Patent and making part of the same, containing a description in the words of the said William A. Turner, being of his improvement in the odometer or machine for indicating the distance travelled in a carriage,--

To all whom it may concern,

Be it known that I William A. Turner of Plymouth in the County of Washington & State of North Carolina, have invented an improvement in the Odometer, or machine for indicating the distance travelled by a wheeled carriage of any description, and I do hereby declare that the following is a full and exact description thereof,

As the mode of applying this instrument to any other carriage will be obvious from the application of the way which I have applied it to a stage or other four-wheeled carriage, I shall in my description confine myself to a vehicle of this kind.

I will a hole longitudinally thro' the centre of the axle of one of the hind wheels, to admit a rod which may recede within the said axle, extending from the outer end thereof, to the middle of the axle. As such axles are usually bent or curved under the body of the carriage, the hole for the rod will, in such case be free from the axle before it reaches the middle thereof, or if straight the rod may be constructed with an eye or opening in the middle, to allow the axle to run or pass thro' it in the manner required. On the outer end of the rod within the end of the hole I attach a pin at right angles thereto, bearing on it a pointed, or bony piece, so constructed that a pin projecting from the inside of the eye of the rod will touch against it, & carry it round in one direction, but in consequence of the bony or joint giving way before the pin it will not turn it in the opposite direction; this is shown at α in the accompanying drawing, β being the rod within the axle; α is at the joint of this rod and will be mounted by screws. The slot after the

carriage, is broken, allows the rod with the machinery attached to remain at rest, entirely to prevent all danger of the wheelwork missing bearings from any stiffness in the axle. I usually place a notched wheel upon some part of the revolving rod, —

That end of the rod which is inwards & which reaches to the middle of the axle has on it a bevel wheel, or an outward screw C which makes or takes into a wheel f, placed upon an axle or revolving rod, at right angles to the former, extending out above the fork & inclining a little sideways towards the body and front end of the carriage. This rod is made to run in proper boxes, or bearings. Soon after it leaves the axle & at any convenient distance therefrom, it is furnished with a universal joint g, in order that it may suffer any necessary deviation from a a straight line, without experiencing a resistance which shall be injurious or obstruct its motion, & when it reaches the bottom of the body of the carriage, or nearly so, I employ a second universal joint h, as the rod at, or near, that point is subject to some change in its direction. — Between these two universal joints, the rod by which the motion is conveyed from the gearing near the axle to a revolving rod or axle i, lying within the body of the carriage is made double as at j, in such a way that one part of it may slide within the other, & admit of its being lengthened or shortened by the pitching of the carriage and its motion from the elasticity of the spring & braces upon which it is hung, whilst at the same time the evolution of the rod itself is not impeded & the universal joints allow a free lateral motion. — One of the most simple ways of forming this slide & which answers perfectly well in practice, is to make one part of the rod a socket with a square hole and the other portion square fitting into & sliding freely in this hole, this rod I denominate the accommodation rod.

At the bottom of & within, or under the body of the carriage, the rod which conveys the motion is boxed up in any convenient way by which means it is defended from injury, it runs in proper bearings, & when its direction is changed as at k-k, this may be done by universal joints or by pins. At its upper end h it has an outward screw, a pinion, a fork and cap or other contrivance by which it may

give motion to the wheelwork and index plates, which I usually place within the carriage near the upper end of the front directly at the back of the driver. - The case however may if preferred be fixed elsewhere.

When used on rail way carriages, the axle of which revolves with the wheels - an endless screw or toothed wheel, is formed or placed upon the middle of the axle. & from this the motion is conveyed to the wheelwork in the manner or upon the principle herein before specified. -

The wheelwork may be constructed in various ways, the number of leaves upon the pinions, & of the teeth upon the wheels, being so calculated as to give the proper indication as dependant upon the circumference of the wheel from which the motion is derived. -

This every competent workman is able to calculate upon principle, which do not require to be explained by me. -

I do not claim the application of wheels, pinions or endless screws, to produce this effect, they having been already applied for a similar purpose; but having devised a combination of well known mechanical contrivances, which is new in its application & arrangement, I consider myself as entitled to this special application & arrangement, which I shall therefore proceed to describe. - The plate upon which the distance travelled, is indicated, I make oblong as seen in fig 2, & usually with four openings, behind which the dials, or plates, having the figures on them revolve, - The right hand opening may show, eighty or other fractional parts of miles, the next units, the next tens, & the next hundreds; these plates are seen at $\frac{1}{10}$, $\frac{1}{100}$, $\frac{1}{1000}$, $\frac{1}{10000}$, as they are made to revolve by a direct motion from their axes they turn in opposite directions, & the figures shown are therefore upon two of them, on the upper and upon the other two upon the lower side of the wheel, as will be seen by inspecting the drawings.

As it is requisite, or most convenient, to give to the wheel an intermitting motion, I employ a kind of escapement wheel and pallet, well known in clock and watch work, in fig 2, figs 1, 2, 3, show the construction of these where $\mathfrak{a}$ being the pallet and $\mathfrak{b}$ the wheel which it turns, the projecting part of the pallet taking into one of the notches, or teeth in the wheel at each revolution in fig 3 acts as a crown wheel, & in fig 4 as a common flat wheel, - the

1844 X

The action throughout the index key is of this character.

I will now give an example of the number on the wheel, which will answer for a coach wheel of four feet in diameter, the winding of the line which goes around in this country. I make the wheel or pinion 1 of iron bars; at or near the point where the rods enter the bottom of the carriage, I place a wheel or pallet n. 0; the wheel having six notches or teeth, the wheel of the first index plate Mr. has eight notches or teeth, & that of each of the others ten.

The pinion f. has eleven bars, & the thread of the axle goes a long single the coach wheel will turn seven times whilst the pinion turns once.

The wheel m. has six teeth and it will therefore turn once whilst the coach wheel turns 7×6 or 42 times. Now upon taking the circumference of a 5 foot wheel with its tire, it will be found that 42 revolutions of such a wheel will carry it to a distance which is equal as measured may be to one eighth of a mile which is indicated by one revolution of the pallet 6, & they are all made with the same number of teeth upon the wheel into which the pallets take, and with the exception of that on the arbor of the first plate, they are all flat wheels.

Fig. 4 shows the carriage and its body, with the accommodation and nearly all the parts of the apparatus which appear externally without the body of the carriage. As it is necessary to secure the part of the apparatus within the cap from injury by dust & otherwise and at the same time to open the cap with facility for the purpose of greasing the axle, I have devised a new mode of fastening the cap on to the end of the hoop, or barrel, of the hub, or nave, this I do by what is called a bayonet joint, having two or more pins projecting from the rim of the cap, which pass into notches on the hoop. & then turn at right angles to lock; or otherwise I make a flange, or rim, to project inward from the edge of the hoop, & in this make two, or more notches, which allow a slip upon the cap to pass thro', turn, and lock upon the flange.

In addition to their being by pins, or slips, I place a spring bolt or catch, which falls into a cavity within the cap & prevents its removal until the bolt-latch or spring is raised; which may be done by a nut, or pin passing thro' a small opening in the cap. Boxes of this article

379

may be applied to all the wheels. The manner of making them may be seen in Fig. 5. It will not require further explanation.

What I claim as my invention and for which I seek a Patent, is the carrying the motion, in the manner described from the centre of the axle toward the body of the carriage, the employment of the sliding rod for the purpose set forth, the giving the indication of the distance travelled within the body of the carriage, & the general manner in which the parts are arranged for effecting the object. I also claim the mode of securing the caps upon the hubs of the wheels, —

(Witness)

Tho. G. Jones
